LOCK

Edward N. Jacobi, Milwaukee, Wis., assignor to
 Briggs & Stratton Corporation, Milwaukee,
 Wis., a corporation of Delaware

Application August 9, 1935, Serial No. 35,492

12 Claims. (Cl. 70—46)

This invention relates to locks and refers more particularly to steering post locks for automobiles.

In locks of this type, a sliding bolt is operable 5 to and from locking engagement with the steering column by the same key controlled lock which serves to lock the ignition switch against actuation. The lock cylinder is mounted with its inner end adjacent the side of the bolt and 10 has a driving connection with the bolt comprising an eccentric cam driven by the cylinder and received in a keeper recess in the bolt. To keep down the over-all size of the locking mechanism, the space allotted to the driving connection between the cylinder and the bolt is necessarily 15 small, which introduces difficulties in the design of the driving connection.

Another important element which must be taken into consideration in the design of the driving connection is the fact that the bolt has 20 a throw greater than it is possible to impart thereto by a cam lying within the diameter of the cylinder so that the cam must extend or overhang the cylinder diameter.

These requirements coupled with the fact that 25 the cylinder must be removable and that the driving connection must be so designed and constructed as to reduce the possibility of wear to a minimum has introduced factors difficult to cope with.

30 In the past, the driving connection between the cylinder and the bolt incorporated an adaptor rotatably mounted in the inner end of the lock casing and to which the eccentric cam was permanently attached. Removability of the lock 35 cylinder was provided by having the connection between the cylinder and the adaptor separable. This construction was difficult to assemble as it required a predetermined position of rotation on the part of the adaptor and also increased the 40 cost of the lock assembly.

With the above and other objections to the 45 past lock assemblies of this character in mind, this invention has as one of its objects to provide an improved construction which obviates the need for an adaptor and in which the driving connection between the cylinder and the eccentric cam is direct.

Another object of this invention is to provide 50 a lock assembly of the character described which is designed so as to facilitate assembly of the parts.

Another object of this invention is to provide 55 a lock assembly of the character described which is so designed that regardless of inevitable play

in the parts comprising the driving connection between the cylinder and the locking bolt, a firm fit will be maintained at all times to reduce the possibility of wear to a minimum.

Another object of this invention is to provide 5 a lock structure of the character described which is stronger against outward stresses applied to the cylinder as in an attempt to destroy the lock.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best 20 mode so far devised for the practical application of the principles thereof, and in which:

Figure 1 is a section view through a lock assembly embodying this invention showing the same in its unlocked position;

Figure 2 is a section view through Figure 1 on the plane of the line 2—2;

Figure 3 is a perspective view of the lock cylinder, its sleeve and the cam roller;

Figure 4 is a section view similar to Figure 2 30 but with the cylinder removed and showing the manner of assembling the cam roller with the bolt; and

Figure 5 is a perspective view of the tool provided for inserting the cam roller, as shown in 35 Figure 4.

Referring now more particularly to the accompanying drawings in which like numerals indicate like parts throughout the several views, the numeral 5 designates the body of the lock mechanism which is designed to embrace a steering column in the conventional manner. Inasmuch as this invention is not concerned with the particular construction of the lock body and its relationship to the steering column and the associated 40 mechanism, these elements have not been shown.

The body 5 has a bore 6 in which a bolt 7 is 45 slideable to lock the steering column (not shown) and the ignition switch (also not shown). The bolt 7 besides being slideable to effect this dual locking function is rotatable by a lever 8 attached thereto for opening and closing the ignition switch when the bolt is in its outermost projected or unlocked position shown in Figure 1.

The actual locking engagement with the steer- 55

ing post is effected by a pin 9 slidably disposed within a bore 10 in the bolt and yieldingly urged outwardly thereof by a spring 11 confined between the inner end of the pin and the bottom of the bore. This arrangement enables the bolt 7 to be moved to its locked position even though the steering column may not be turned to align its keeper recess with the axis of the bolt.

To retract the pin 9 with the outward unlocking movement of the bolt 7, a stop 12 is fixed to the bolt and engages with an abutment formed by the outer end of a recess 13 in the side of the pin.

Intersecting the bore 6, the body 5 has a bore 14 counterbored at its outer end as at 15. A lock sleeve 16 is fixed in the bore 14 by a pin 17. The outer end of the sleeve terminates flush with the bottom of the counterbore 15 and its inner end is spaced a short distance from the side of the bolt, as shown.

20 The sleeve 16 has a lock cylinder 18 rotatably received in its bore 19, the outer enlarged head 20 of the cylinder being disposed in the counterbore 15. The cylinder is held against withdrawal from the sleeve by a lug 21 projecting into its bore 25 to be received in an annular groove 22 in the inner end portion of the cylinder. To enable engagement of the lug 21 in the annular groove 22 during insertion of the cylinder, a gateway 23 opening to the extreme inner end of the cylinder 30 communicates with the annular groove. The annular groove and the gateway 23 together form a bayonet slot and obviously the engagement of the lug 21 therewith is possible only when the cylinder is in a predetermined position of rotation 35 with respect to the sleeve.

Within the normal limits of rotation of the cylinder during the performance of its locking functions, the cylinder does not reach this position at which the gateway 23 aligns with the lug 21. These normal limits of rotation of the cylinder are defined by the engagement of a stop lug 24 on the inner face of the cylinder head 20 abutting cooperating abutments on the sleeve 16. The sleeve abutment incorporates a depressible pin 45 26 which upon depression by a tool inserted through a hole in the head of the cylinder permits the passage of the abutment 24 and allows rotation of the cylinder beyond one of its normal limits to a point aligning the gateway with the lug 21.

As long as the gateway 23 is not aligned with the lug 21, the cylinder is held against withdrawal from the casing by the flange through which the gateway extends. Heretofore, no attempt was 55 made to strengthen this flange and it was found that the lock was often destroyed by an outward pull exerted on the cylinder, this being done by screwing a lag screw into the mouth of the keyway and applying a wheel puller thereto. To 60 guard against this possibility, the inner end of the lock cylinder is reinforced by a lug 28 and an eccentric post or lug 29 which serves to drivingly connect the cylinder and the bolt 7 in a manner to be hereinafter more fully described.

65 As will be readily apparent, the presence of the lug 28 and eccentric post 29 provides a substantial body of metal back of the flange at the inner end of the cylinder and thus precludes shearing off part of the flange by an outward pull on the 70 cylinder.

75 Rotation of the cylinder is normally prevented by tumblers 30 movable diametrically through the cylinder and yieldingly projectible into diametrically opposite tumbler receiving grooves 31 in the casing. The tumblers are retractible out of

the grooves by the insertion of a proper key 32 to free the cylinder for rotation.

It will be observed that the eccentric driving lug 29 is at the extreme edge of the cylinder and that it is so disposed on the lock cylinder that at both limits of rotation of the lock cylinder (one hundred and eighty degrees), the lug 29 is in line with the axis of the sliding bolt 7 so that the maximum throw of the eccentric lug is utilized for actuating the bolt.

10 However, the amount of motion which can be produced by a cam lying entirely within the diameter of the cylinder is insufficient and does not move the bolt its required distance. Consequently, the effective throw of the eccentric driving lug must be increased and this is accomplished by the provision of a cam roller 33.

15 The cam roller has an outside diameter substantially greater than that of the eccentric driving lug so that it extends a substantial distance 20 beyond the diameter of the cylinder. One end portion 34 of the roller is received in a keeper recess 35 in the bolt 7. This end portion 34 of the cam roller is slightly smaller in outside diameter than its remaining portion 36 to provide an abrupt 25 shoulder 37 medially of the length of the roller which engages with the curved surface of the bolt at the sides of the keeper recess 35 to limit the longitudinal drift of the cam roller on its eccentric driving post 29.

30 However, even though the parts be fitted as closely as adequate clearance will permit, a substantial degree of longitudinal drift or relative endwise motion between the cam roller and its eccentric driving lug cannot be avoided. This together with the fact that the driving lug must be tapered at its outer end to facilitate its insertion into the cam roller during assembly of the parts and as the length of the roller is limited by the 40 restricted space between the inner end of the cylinder and the side of the bolt, a uniform internal diameter of the cam roller would result in a condition where the application of force on the roller during the actuation of the bolt might cause a tendency to cock or tip the roller on its driving 45 lug thus causing excessive wear.

To overcome this objectionable possibility and at the same time provide effective means for piloting the driving lug into the cam roller, the internal diameter of the cam roller is not uniform 50 but has a small diameter 40 at one end and a large internal diameter 41 at its other end connected by a tapered bore 42. The outside diameter of the eccentric driving lug or post 29 corresponds to these inside diameters of the roller so that when the post is inserted into the roller to its fullest extent, all portions of the multiple diameter bore of the cam roller will be properly engaged with the corresponding portions of the driving post.

55 This multiple diameter of the post and cam roller bore eliminates the necessity for a tapered or beveled end on the post for the sake of piloting the same into the roller and provides a construction whereby a journal support will be maintained at both ends of the cam roller throughout the range of permitted relative longitudinal motion between the roller and the driving post. Tipping or cocking of the roller on its post is thus prevented.

60 In assembling the lock mechanism, the cam roller is disposed in the chamber between the inner end of the casing and the side of the bolt by means of a tool 43. This tool consists of a rod having an end portion thereof slotted off as at 65 44 and bifurcated to provide two spring fingers. 70 75

The outer extremities of these fingers are shaped to engage in the bore of the cam roller and hold the roller on the tool as shown in Figure 4. Through the medium of this tool, the cam roller is easily inserted through the bore of the lock casing into proper engagement with the keeper recess of the bore. Then with the roller so positioned, the tool 43 is withdrawn and the cylinder inserted in the usual manner.

10 In view of the correlative shapes of the lug 29 and the bore of the cam roller, engagement of the lug in the bore of the roller during insertion of the cylinder is facilitated.

From the foregoing description taken in connection with the accompanying drawings, it will be readily apparent to those skilled in the art to which this invention appertains, that this invention provides a substantial improvement in the driving connection between the lock cylinder and bolt of steering post locks and that as a result of this improvement, assembly of the lock mechanism is materially facilitated and the cost thereof is reduced. It is also apparent that this invention adds to the security of the lock by strengthening the same against forced outward withdrawal of the lock cylinder.

What I claim as my invention is:

1. In a lock assembly of the character described, a body having intersecting bores, a bolt 30 slidable in one bore, a lock cylinder rotatable in the other bore with its inner end spaced from the side of the bolt, an eccentric post projecting from the inner end of the cylinder as an integral part thereof, and a cam roller disposed in a 35 chamber between the inner end of the cylinder and the side of the bolt and confined against displacement by the bolt and one wall of the chamber with a portion thereof received in a keeper recess in the bolt and having a bore to 40 receive the post, said post being at the extreme edge of the cylinder whereby the roller overhangs the diameter of the cylinder and is operable by rotation of the cylinder to slide the bolt a substantial distance.

45 2. In a lock assembly of the character described, a body having intersecting bores, a sliding bolt in one bore, key controlled means for actuating the bolt disposed in the other bore and comprising a sleeve fixed in said second 50 designated bore with its inner end spaced from the side of the bolt, a lock cylinder slidably insertable into the sleeve and rotatable therein, a cam roller in the inner end of the second designated bore between the inner end of the sleeve 55 and the bolt and confined against displacement by the bolt and the inner end of the sleeve with a part extending into a recess in the side of the bolt, the outer diameter of said roller being such that when the roller rests in position, its bore is directly accessible from the bore 60 of the sleeve, and an eccentric driving post projecting from the inner end of the cylinder and readily insertable into the cam roller as the cylinder is inserted into the sleeve, said driving post being on the extreme edge of the cylinder 65 so that the cam roller extends beyond the diameter of the cylinder.

70 3. In a lock assembly of the character described, a body having intersecting bores, a bolt slidable in one bore, a lock sleeve fixed in the other bore with its inner end spaced from the side of the bolt, a lock cylinder slidably insertable into the sleeve and rotatably secured therein with the inner end of the cylinder proper substantially flush with the inner end of the sleeve,

a cam post extended from the inner end of the cylinder as an integral part thereof across said space between the casing and the side of the bolt, and a cam roller readily removably mounted on said post and held thereon by being confined between the side of the bolt and the inner end of the sleeve, said cam roller having an outer diameter such that with the roller resting on the wall of the bore in which the sleeve is secured the cam post may be aligned therewith for direct insertion into the roller as the cylinder is inserted into the sleeve and an end portion on the cam roller disposed in a keeper recess in the bolt so that rotation of the cylinder imparts sliding movement to the bolt.

15 4. In a lock assembly of the character described, a body having intersecting bores, a bolt slidable in one bore, a lock sleeve fixed in the other bore with its inner end spaced from the side of the bolt to define a chamber at the inner end of the sleeve, a lock cylinder rotatably mounted in the sleeve and insertable from the outer end thereof, an eccentric driving lug projecting from the inner end of the cylinder as an integral part thereof, and a cam roller positionable in said space at the inner end of the sleeve through the bore in the sleeve with a part thereof extending into a keeper recess in the bolt, said cam roller having a bore to receive the eccentric driving lug on the cylinder as the cylinder 20 is inserted into the sleeve and being confined against displacement by the side of the bolt and the inner end of the sleeve, said roller being of such diameter that when resting on the wall of the chamber bore it is in line with the driving 25 lug to directly receive the same upon insertion of the cylinder.

5. In a lock assembly of the character described, a body having intersecting bores, a bolt slidable in one bore, a lock sleeve fixed in the other bore with its inner end spaced from the side of the bolt to define a chamber, a cam roller positioned in said chamber by being inserted through the bore in the sleeve with a portion thereof received in a keeper recess in the bolt and 40 confined against displacement by the side of the bolt and the inner end of the sleeve, a lock cylinder rotatable in the sleeve and insertable therein from the outer end thereof, and an eccentric driving lug projecting from the inner end of the cylinder as an integral part thereof to engage in a bore in the cam roller and provide a driving 45 connection between the cylinder and roller by which the roller and cylinder are connected with the roller extending beyond the diameter of the 50 cylinder.

6. In a lock assembly of the character described, a rotatable lock cylinder, an eccentric driving post projecting from the end of the cylinder as an integral part thereof, a cam roller 60 bored to receive the post, said post having an outer end portion smaller in diameter than its base portion, and the bore in the cam roller having portions of corresponding different diameters so that a firm bearing is provided between the post and roller near the ends of the roller throughout 65 a degree of relative endwise motion between the cam roller and the post and at the same time engagement of the post into the bore of the roller is facilitated by the piloting effect of the small 70 diameter outer end of the post entering the large diameter portion of the roller bore.

7. In a lock assembly of the character described, a body having intersecting bores, a bolt 75 slidable in one bore and having a keeper recess

in its side accessible from the other bore, a cam roller positionable in the inner end of the other bore with a portion thereof received in the keeper recess of the bolt, a lock cylinder to drive the cam roller rotatable in said other bore and insertable therein from its outer end, and an eccentric driving post projecting from the inner end of the cylinder as an integral part thereof and received in a bore in the cam roller, the post having an 5 outer end portion of smaller diameter than its base portion and the bore in the cam roller having portions of corresponding large and small diameters so that insertion of the post into the bore of the roller is facilitated by the piloting 10 effect of the small outer end portion of the post entering the large diameter part of the bore in the roller, and said large and small diameter portions of both the post and the bore in the roller being parallel with the axis of the post and roller 15 so that firm bearings are maintained at opposite ends of the roller throughout a degree of relative longitudinal movement between the post and roller.

3. In a lock assembly of the character described, a body having intersecting bores, a bolt 20 slidable in one bore and having a keeper recess in its side accessible from the other bore, a rotatable lock cylinder in said other bore with its inner end spaced from the side of the bolt, said cylinder being insertable into said other bore through the open outer end thereof, an eccentric driving post extending from the inner end of the lock cylinder as an integral part thereof and projecting into the keeper recess in the bolt, and a 25 cam roller journaled on said post and held thereon by being confined between the inner end of the cylinder and the side of the bolt, part of said roller extending into and having close engagement with the sides of the keeper recess in the bolt, and the engagement between the driving post and the cam roller being such that a firm 30 bearing is maintained between the post and the roller at both ends of the roller throughout a degree of relative longitudinal motion between the post and roller permitted by the necessary play in the parts while at the same time a piloting effect is obtained to facilitate engagement of the post in the bore of the roller.

9. In a lock assembly of the character described, a body having intersecting bores, a bolt 35 slidable in one bore and having a keeper recess in its side accessible from the other bore, a lock sleeve fixed in said other bore with its inner end spaced from the side of the bolt to define a chamber, a lock cylinder rotatable in the sleeve and insertable through the outer open end thereof, the inner end of the cylinder being substantially flush with the adjacent inner end of the sleeve, an eccentric driving post extending from the inner end 40 of the cylinder as an integral part thereof and projecting into the keeper recess in the bolt, and a cam roller disposed in said chamber at the inner end of the sleeve with a portion thereof snugly received in the keeper recess of the bolt and having a bore to rotatably receive the driving post, said driving post being at the extreme edge of the cylinder so that the cam roller extends beyond

the diameter of the cylinder, and said cam roller being held on the driving post by being confined between the inner ends of the cylinder and sleeve and side of the bolt and the bore in the cam roller as well as the outside diameter of the post being of multiple diameter with the outer end portion of the post of smallest diameter so as to afford a firm bearing between the cam roller and post throughout a degree of endwise displacement between the roller and the post permitted by the play in the parts while at the same time engagement of the post in the bore of the roller is facilitated by the piloting effect of the small end of the post entering the large diameter of the roller bore. 5 10

10. In a lock assembly of the character described, a bored lock casing, a cylinder rotatable in the casing, said cylinder having an annular groove adjacent its inner end so that the metal left between the groove and the inner end forms a narrow flange, a lug extending into the casing bore to be received in said annular groove to hold the cylinder in the casing, said lug being engageable in the groove when the cylinder is in a predetermined position of rotation through a gateway in the narrow flange leading to the groove, and a plurality of lugs extending from the inner end of the cylinder as integral parts thereof to strengthen the narrow flange, and one of said lugs providing an eccentric driving post for translating rotation of the lock cylinder into sliding movement on the part of instrumentalities to be controlled by the lock, said eccentric driving post being adapted to receive a roller and being separated from the other lugs to accommodate wall thickness of such roller. 20 25 30 35

11. In a lock device, a key operable rotatable lock cylinder, an eccentric driving lug projecting from one end of the cylinder, and a cam roller 40 removably mounted on said driving lug, said driving lug being of multiple diameter with its smallest diameter outermost, and the cam roller having a bore of corresponding multiple diameter so as to provide a firm bearing between the lug and roller at opposite ends of the roller bore while at the same time facilitating engagement of the lug in the roller bore by the piloting effect of the small diameter end of the lug entering the large diameter end of the roller bore. 45

12. In a lock device, a rotatable lock cylinder, an eccentric driving lug projecting from the cylinder as an integral part thereof through which rotation of the lock cylinder may be translated into sliding movement of a part to be actuated, and a cam roller removably and rotatably disposed on said lug, said lug having a large diameter inner end portion and a small diameter outer end portion connected by a medial tapered portion, and the cam roller having a multiple diameter bore corresponding in size and shape to the eccentric lug so as to provide firm journal bearings at opposite ends of the roller and at the same time facilitate engagement of the lug in the bore of the roller through the piloting action of its inner end entering the large diameter end of the bore in the roller. 50 55 60 65
